(57) **CLAIM**

I claim the ornamental design for a children's playground rocker in the shape of peas in a pod, as shown and described.

DESCRIPTION

FIG. 1 is a front elevational view of a children's playground rocker in the shape of peas in a pod showing my new design; FIG. 2 is a right side elevational view thereof, (the left side elevational view being a mirror image of the right side elevational view);

FIG. 3 is a top plan view thereof;

FIG. 4 is a rear elevational view thereof; and, FIG. 5 is a bottom plan view thereof.
